UNITED STATES PATENT OFFICE

HERMANN KLAUCKE, OF WORCESTER, MASSACHUSETTS, ASSIGNOR, BY MESNE ASSIGNMENTS, TO L. H. HAMEL LEATHER CO., OF HAVERHILL, MASSACHUSETTS, A CORPORATION OF MASSACHUSETTS

CONVEYER SYSTEM FOR MANIPULATING FLAT ARTICLES

Application filed June 5, 1929. Serial No. 368,640.

This invention relates to certain improvements in conveyer systems primarily designed to be employed in connection with the system disclosed in the patent to L. H. Hamel No. 1,830,359, dated November 3rd, 1931, for means for stretching and drying skins, in which a series of flat holders, or boards are provided, on the opposite sides of which the skins are stretched and secured by tacks, the stretching and tacking-on operation being performed while the boards are conveyed horizontally in one direction, after which the boards are automatically delivered to a drying room, through which they are slowly passed, so that the drying operation is performed by the time they emerge from the drying room, then they are returned to the starting point, and the dried skins are removed and fresh skins are applied.

The boards are thus carried thru a complete cycle of operations in an endless path, and in the preferred embodiment of the system a series of conveyers are provided, from one to another of which the boards are successively transferred, so that the boards are carried in an endless, vertically disposed path, the arrangement being such that the boards are carried horizontally by a primary conveyer at a convenient low level, while the tacking-on operation is performed, then are transferred to a slow moving conveyer in the drying room, by which they are carried from the front to the rear end of this room, then are raised and moved in the opposite direction at a higher level, then are delivered from the room at this level to a returning conveyer, which carries them back over the primary conveyer and then lowers them to the original level and delivers them to the primary conveyer, so that the operation may be repeated.

In order that the boards may be conveniently handled in this manner, each board is provided with trunnions at its opposite edges and in axial alignment at one side of its center of gravity, and each conveyer comprises a pair of chains between which the boards are supported and with which the trunnions are respectively engaged.

In automatically transferring the boards

from one conveyer to another as they are moved about the circuit, different conditions are encountered, which requires different transferring means, one of the more difficult of which is in lowering the boards from the overhead returning conveyer to the end of the primary conveyer, so that the boards will be delivered from one to the other in perfect time and without appreciable strain on, or shock to the parts.

The object of the present invention is to provide a suitable, reliable and effective means for transferring the boards from a conveyer arranged to carry the boards horizontally at a certain high level and to deliver them to another conveyer arranged directly therebeneath in predetermined time and without undue strain on the parts.

These objects are accomplished by means of the construction and arrangement herein-after described and illustrated in the accompanying drawings, in which:

Fig. 1 is a side elevation of one end portion of the system.

Fig. 2 is a plan view thereof.

Fig. 3 is a view similar to Fig. 1, on a somewhat larger scale illustrating the invention more in detail.

Fig. 4 is a detail view of one of the locking latches which is employed.

Fig. 5 is a sectional view at line 5—5 of Fig. 4.

For the purposes of the disclosure of the invention claimed herein, it is unnecessary to describe all of the mechanism which is employed in conducting the boards throughout the circuit hereinbefore referred to, consequently, the disclosure hereinafter made will be confined to those parts which are directly associated with said invention.

The primary conveyer comprises a pair of endless chains 6, 6, each of which is driven horizontally in the direction of the arrow in Fig. 1, about an end sprocket 7, on shaft 7', said chains being provided with projecting fingers 8 at suitable intervals for engagement with the trunnions 9 of the boards 10, the latter being the particular articles to be conveyed. The trunnions of each board are arranged to project in axial alignment from

its opposite edges and the axial line thereof is located at one side of the center of gravity, so that when supported by the trunnions only the board will be held in a vertical position by its gravity. Horizontal tracks 11 are provided in conjunction with the chains 6, 6, so that for a portion of the distance which the boards are propelled by said chains, they may be held in a horizontal position, in which position the tacking-on operation, above referred to, is performed. The returning conveyer also comprises a pair of endless chains 12, which are also arranged in parallelism, and driven horizontally, said chains being carried about end sprockets 13 mounted on a shaft 30 supported in the frame 32 of the machine. Said chains 12 are also provided with projecting fingers 14 for engagement with the trunnions of the boards and are driven in the direction indicated by the arrow adjacent thereto in Fig. 1, so that the top portions of chains 12 travel in the opposite direction to the top portions of the lower, or primary chains 6. Tracks 15 are also provided for holding the boards in a horizontal position as they are propelled by the chains 12.

As completely disclosed in said application of L. H. Hamel, the skins are stretched and tacked onto the boards as they are drawn along on the tracks 11 by chains 6, and are delivered to a drying room and carried therethrough at about the level of the chains 6, then are lifted and returned at about the level of the chains 12 and transferred to the latter and moved horizontally on the tracks 15 towards the sprockets 13, so that as they are being returned they will not hang down and strike the operators who will be engaged in tacking the skins onto the boards while carried by the primary conveyer.

As previously indicated, it is necessary that the boards, as they are returned by the chains 12, be redelivered to the chains 6, and, for this purpose, the sprockets 13 are made of a diameter nearly equal to the distance between the operating portions of the chains 6 and 12. Also a series of bell-crank shaped latches 16 are mounted on pivots 17 fixed in the peripheral portion of the sprockets 13, said latches being spaced apart about the periphery at distances corresponding to the distance between the fingers 14 on the chains 12. One arm of each latch is provided with a hook shaped end portion 18 and the other arm has a roller 19, arranged for engagement with an elongated cam plate 20, which is fixed on the frame 32 and has an inclined end face 21 and a circular edge face 22 arranged concentrically with the sprockets 13, said plate being extended from a point directly above shaft 30 to a point beneath it. A coil spring 23 is attached to each latch and to the sprocket and normally holds the arm of the latch to

which it is attached against a stop 23 on the sprocket.

The tracks 15 are terminated adjacent the sprockets 13, so that, as each board is moved into proximity to the sprockets 13 it is withdrawn from the tracks and by its gravity swings into a vertical position, as indicated in Fig. 1, and, then by engagement with an abutment 24, is swung forward sufficiently to clear the shaft 30, and then is permitted to swing back to the vertical position. The timing of the chains with relation to the sprockets 13 is such that as each finger 14 on the chains 12 is moved into proximity to a position directly over the axis of the sprockets 13, the roller 19 on one of the latches 16 will be engaged with the cam face 21, so that the arm having the hook shaped end portion 18 will be swung into engagement with one side of a trunnion 9, which will be engaged at its opposite side by a finger 14, and, as a result, by the time the roll 19 passes onto the circular cam face 22, the trunnions 9 of the board will be clasped between the latch and the finger, as shown in detail in Fig. 4, in which position the trunnions will be free to turn, but will otherwise be held against movement relatively to the chains 12 or sprockets 13. This condition will continue until the trunnions 9 have been carried down through a path of nearly 180°, or nearly to a point directly beneath the axis of the sprockets 13, at which point the roller 19 on the latch will be moved out of contact with the circular face 22 and into engagement with an inclined abutment 25 on the frame, causing the latch to be swung back to normal position and out of engagement with the trunnions, the arrangement being such that this occurs at approximately the instant the trunnion is at the lowest point of its travel while engaged with the chains 12.

As shown in Figs. 1, 2, and 3, the sprocket 13 is mounted directly over the chains 6, as they extend from their sprockets 7, so that when the trunnions 9 are disengaged from the latches they will be permitted to fall onto the chains 6, which are driven in as close proximity to the chains 12 as is practical. As a result, the board will then be supported by the chains 6 and trunnions 9 thereof will be engaged by the fingers 8 of the chains, so that the board will be carried on thereby. The operation of transferring the boards from the return conveyer to the primary conveyer is thus performed without undue strain, or sudden shocks to the parts, as the arrangement is such that, by the time the latches are disengaged from the trunnions, the latter will have been carried practically into engagement with the chains 6, so that distance which the boards fall in being transferred is inappreciable.

After the boards have been returned to the primary conveyers the dried skins will be removed and fresh skins will be tacked on, so

that the operation may be carried on continually.

What is claimed is:

1. In a system for conveying articles having oppositely projecting trunnions, a delivering conveyer comprising a pair of endless chains and wheels at the delivery end of the conveyer about which the chains are driven downwardly, engaging means on said chains for said trunnions, whereby the articles are propelled thereby towards said wheels and means on said wheels for supporting the trunnions in proximity to their respective engaging means, while they are moved downwardly about the wheels and until the articles have been lowered to a delivery position. 70
2. In a system for conveying articles having oppositely projecting trunnions, a delivering conveyer comprising a pair of endless chains arranged to be driven horizontally and having wheels about which they pass downward at the delivery end of the conveyer, projections on the top sides of said chains for engaging said trunnions, to hold them in predetermined positions on the chains while in the horizontally driven positions thereof, thereby to convey the articles successively in spaced relation, and retaining means on said wheels for holding each pair of trunnions in approximately said positions with relation to the chains while the projections thereof are being moved downwardly about said wheels and until the articles have been lowered to a delivery position. 75
3. In a system for conveying articles having oppositely projecting trunnions, a delivering conveyer comprising a pair of endless chains arranged to be driven horizontally and having wheels about which they pass downward at the delivery end of the conveyer, means on the top sides of said chains for engaging said trunnions, to hold them in predetermined positions on the chains while in the horizontally driven positions thereof, thereby to convey the articles successively in spaced relation, retaining devices on each wheel arranged for engagement with the trunnions to hold them in approximately said positions with relation to the chains while the engaging means thereof is being moved downwardly about the wheels, and means to move said retaining devices to disengage them from the trunnions when the articles have been lowered to a delivery position. 80
4. In a system for conveying articles having oppositely projecting trunnions, a delivering conveyer comprising a pair of endless chains arranged to be driven horizontally and having wheels about which they pass downward at the delivery end of the conveyer, means on the top sides of said chains for engaging said trunnions, to hold them in predetermined positions on the chains while in the horizontally driven positions thereof, thereby to convey the articles successively in spaced relation, latches on said wheels arranged to engage said trunnions as they are moved over to top portion of the wheels and to hold the trunnions in corresponding positions relative thereto as the latches are moved downwardly and means for moving said latches to release the trunnions when the articles have been lowered to a delivery position. 85
5. In a system for conveying articles having oppositely projecting trunnions, a delivering conveyer comprising a pair of endless chains arranged to be driven horizontally and having wheels about which they pass downward at the delivery end of the conveyer, a series of spaced projections on the top sides of said chains for engaging said trunnions while resting thereon, to cause the articles to be propelled as the chains are driven, latches pivoted on said wheels and projecting beyond the peripheries thereof in position. 90
6. In a system for conveying articles having oppositely projecting trunnions, a delivering conveyer comprising a pair of endless chains arranged to be driven horizontally and having wheels about which they pass downward at the delivery end of the conveyer, means on the top sides of said chains for engaging said trunnions, to hold them in predetermined positions on the chains while in the horizontally driven positions thereof, thereby to convey the articles successively in spaced relation, latches on said wheels arranged to engage said trunnions as they are moved over to top portion of the wheels and to hold the trunnions in corresponding positions relative thereto as the latches are moved downwardly and means for moving said latches to release the trunnions when the articles have been lowered to a delivery position. 95
7. In a system for conveying articles having oppositely projecting trunnions a delivering conveyer comprising a pair of endless chains arranged to be driven horizontally and having wheels about which they pass downward at the delivery end of the conveyer, a series of spaced projections on the top sides of said chains for engaging said trunnions while resting thereon, to cause the articles to be propelled as the chains are driven, latches pivoted on said wheels and projecting beyond the peripheries thereof in position. 100
8. In a system for conveying articles having oppositely projecting trunnions, a delivering conveyer comprising a pair of endless chains arranged to be driven horizontally and having wheels about which they pass downward at the delivery end of the conveyer, means on the top sides of said chains for engaging said trunnions, to hold them in predetermined positions on the chains while in the horizontally driven positions thereof, thereby to convey the articles successively in spaced relation, latches on said wheels arranged to engage said trunnions as they are moved over to top portion of the wheels and to hold the trunnions in corresponding positions relative thereto as the latches are moved downwardly and means for moving said latches to release the trunnions when the articles have been lowered to a delivery position. 105
9. In a system for conveying articles having oppositely projecting trunnions, a delivering conveyer comprising a pair of endless chains arranged to be driven horizontally and having wheels about which they pass downward at the delivery end of the conveyer, a series of spaced projections on the top sides of said chains for engaging said trunnions while resting thereon, to cause the articles to be propelled as the chains are driven, latches pivoted on said wheels and projecting beyond the peripheries thereof in position. 110
10. In a system for conveying articles having oppositely projecting trunnions, a delivering conveyer comprising a pair of endless chains arranged to be driven horizontally and having wheels about which they pass downward at the delivery end of the conveyer, means on the top sides of said chains for engaging said trunnions, to hold them in predetermined positions on the chains while in the horizontally driven positions thereof, thereby to convey the articles successively in spaced relation, latches on said wheels arranged to engage said trunnions as they are moved over to top portion of the wheels and to hold the trunnions in corresponding positions relative thereto as the latches are moved downwardly and means for moving said latches to release the trunnions when the articles have been lowered to a delivery position. 115
11. In a system for conveying articles having oppositely projecting trunnions, a delivering conveyer comprising a pair of endless chains arranged to be driven horizontally and having wheels about which they pass downward at the delivery end of the conveyer, a series of spaced projections on the top sides of said chains for engaging said trunnions while resting thereon, to cause the articles to be propelled as the chains are driven, latches pivoted on said wheels and projecting beyond the peripheries thereof in position. 120
12. In a system for conveying articles having oppositely projecting trunnions, a delivering conveyer comprising a pair of endless chains arranged to be driven horizontally and having wheels about which they pass downward at the delivery end of the conveyer, means on the top sides of said chains for engaging said trunnions, to hold them in predetermined positions on the chains while in the horizontally driven positions thereof, thereby to convey the articles successively in spaced relation, latches on said wheels arranged to engage said trunnions as they are moved over to top portion of the wheels and to hold the trunnions in corresponding positions relative thereto as the latches are moved downwardly and means for moving said latches to release the trunnions when the articles have been lowered to a delivery position. 125
13. In a system for conveying articles having oppositely projecting trunnions, a delivering conveyer comprising a pair of endless chains arranged to be driven horizontally and having wheels about which they pass downward at the delivery end of the conveyer, a series of spaced projections on the top sides of said chains for engaging said trunnions while resting thereon, to cause the articles to be propelled as the chains are driven, latches pivoted on said wheels and projecting beyond the peripheries thereof in position. 130

tion to engage said trunnions as the chains pass onto said wheels and hold them in proximity thereto as they are moved downwardly about the wheels and means to move said latches to disengage the same from the trunnions at a low point in the travel of the wheels and permit delivery of the articles.

8. In a system for conveying articles having oppositely disposed supporting trunnions,

- 10 a primary conveyer comprising a pair of chains arranged to run horizontally and on which the trunnions are supported as the articles are conveyed thereby, a delivery conveyer comprising a pair of chains arranged to run horizontally directly above the corresponding chains of the primary conveyer and having wheels about which the chains thereof are driven to pass downwardly into proximity to the chains of the primary conveyer, said delivery conveyer chains having engaging means on their top sides for supporting the trunnions in predetermined positions thereon as they convey the articles towards said wheels, retaining means on said wheels operatively actuated to hold the trunnions in said positions on the delivery chains against the action of gravity as they are carried downwardly about said wheels and means for moving said retaining means to disengage the same from the trunnions to permit the trunnions to move by gravity onto said primary conveyer chains as they are carried into proximity thereto.

9. In a system for conveying articles having oppositely disposed supporting trunnions,

- 35 a primary conveyer comprising a pair of chains arranged to run horizontally and on which the trunnions are supported as the articles are conveyed thereby, a delivery conveyer comprising a pair of chains arranged to run horizontally directly above the corresponding chains of the primary conveyer and having wheels about which the chains thereof are driven to pass downwardly into proximity to the chains of the primary conveyer, said delivery conveyer chains having abutments on their top sides for holding the trunnions in a series of predetermined positions thereon as they convey the articles towards said wheels, a series of latches operatively movable to hold said trunnions in said positions as they are carried downwardly about said wheels, a fixture extending throughout approximately the entire length of the downwardly extending portion of the path of said delivery conveyer chains and having a face arranged to hold said latches in operative position and to permit movement of such latch to an inoperative position as the trunnion with which it is engaged is moved into proximity to the primary conveyer chains to permit gravity transfer thereof to the latter.

- 60 10. In a system for conveying articles having oppositely disposed supporting trunnions, a primary conveyer comprising a pair

of chains arranged to run horizontally and on which the trunnions are supported as the articles are conveyed thereby, a delivery conveyer comprising a pair of chains, arranged to run horizontally directly over the corresponding chains of the primary conveyer, and having wheels about which the chains thereof are driven to pass downwardly into proximity to the chains of the primary conveyer, engaging means on the top sides of said delivery conveyer chains for supporting the trunnions in predetermined positions thereon as they convey the articles towards said wheels, locking means on said wheels operative to hold the trunnions in said positions as they are carried downwardly about the wheels, and means for disengaging said locking means from the trunnions as they are carried into proximity with said primary conveyer chains, to permit the same to become engaged therewith by gravity action.

In testimony whereof I have hereunto affixed my signature.

HERMANN KLAUCKE
